HERMANN J. SCHUBERT, OF HACKENSACK, NEW JERSEY.

MEASURING AND MOLDING DEVICE.

1,390,590.

Specification of Letters Patent. Patented Sept. 13, 1921.

Application filed December 29, 1917. Serial No. 209,419.

To all whom it may concern:

Be it known that I, HERMANN J. SCHUBERT, citizen of the United States, residing at Hackensack, Bergen county, New Jersey, have invented new and useful Improvements 5 in Measuring and Molding Devices, of which the following is a specification.

My invention relates to mechanism for separating and removing from a mass of 10 material a portion thereof of predetermined quantity and form.

An object of my improvement is to provide a device for transferring from bulk form to comparatively small receptacles 15 definite quantities of a plastic-like medium which it is desired to handle conveniently, and it is inserted neatly into containers of predetermined dimensions.

Another object of my device is to prevent 20 unnecessary waste of the material being handled thereby, both in determining the exact amount to be taken and in so controlling the selected portion as to avoid portions inadvertently dropping or falling off.

A further object of my invention is to 25 provide in connection with the device described automatic means for cleansing the parts which contact the medium handled thereby at the proper stages of the operating 30 thereof.

Generally described my invention comprises a frame having a handle piece at the top and oppositely disposed blades constituting what may be termed cutting jaws 35 which are located at the opposite or bottom end of the frame and are employed for cutting out the material, and which are pivotally supported thereon and adapted to be carried into two operable positions by means 40 of a second handle or gripping bar below the handle of the frame. To accomplish this the device is thrust downwardly or longitudinally into the material to which the device is adapted while in their first or normal position to a depth determined by a transversely disposed gage plate, and then to cut in a horizontal or lateral direction underneath the load until the cutting edges of the blades are brought together, the blades being 45 thus pivotally operated at the end of the downward thrust. The device is then lifted bodily as the blades return to their normal

position at the sides of the portion thus being removed from the bulk quantity by gripping the under handle; whereupon by operation of a hand lever the blades may be forced apart to facilitate the free discharge of the 55 contents into the receptacle provided therefor.

The transverse gage plate that limits the 60 depth to which the tool may be inserted, is slidably mounted in the frame and is actuated to move downwardly by spring action, but is set by hand and held in normal gaging position by a latch device with means 65 for releasing the latch operated by action of the blade spreading mechanism. The gage plate in first pressing upon and then pushing out the measured contents will frequently be found to have particles of the 70 medium adhering to its under face. To remove such accumulations two similar scraping blades are provided normally resting immediately against the surfaces of the pusher gage at the opposite ends and by 75 means of lever arms are thrown together with their edges contacting as the gage plate is forced downwardly in expelling the load. Special mechanism is provided whereby the cleansing blades do not scrape across the 80 surface of the pusher plate until the member is nearing the end of its drop and both the pusher plate and the blades scraping its surface reach the end of their movements simultaneously, the two mechanisms being 85 operated by the same spring motive means.

More specifically considered with reference to its uses, my improvement has been designed more particularly for forming small quantities of ice cream into shapes 90 corresponding to prepared containers, which ordinarily are somewhat rectangular in form. These receptacles are now being filled for the most part by an ordinary kitchen spoon, the spherical bowl of which is 95 small and shallow, and in consequence successive small portions are dished out and inserted with more or less care and effort, each portion being forced down upon the top of the preceding contribution until the 100 approximate amount is obtained. Furthermore, in pursuing the irksome process described, it frequently occurs that small portions of the cream are lost or require re-

handling by falling to the table or elsewhere, which annoying disadvantages are entirely eliminated by the use of my improved filler and measurer.

5 Referring to the drawings of my specification illustrative of a preferred form of the present invention:

Figure 1 is a front elevation of an embodiment of my invention;

10 Fig. 2 is a side elevation of the device as shown in Fig. 1;

Fig. 3 is an inverted sectional view on line 3—3 of Fig. 1;

15 Fig. 4 is a sectional view upon lines 4—4 of Fig. 2;

Fig. 5 is a partial side view similar to Fig. 2, but reduced in size and showing cutting blades having been moved into contacting position at bottom of frame.

20 Fig. 6 is an end view similar to Fig. 2 with cutting blades spread apart;

Fig. 7 is a partial view showing lever supports of pusher blade partially extended; and

25 Fig. 8 is a partial view showing pusher plate levers partially hidden, but fully extended.

Having reference to the drawings: The frame of the preferred form of device illustrated is represented by the numeral 1, which comprises a handle 2 and the similar side portions 3 extending downwardly from the handle almost to the bottom of the device. Near the lower ends of the respective side pieces 3 are pivotally mounted two similar blade members 10, oppositely disposed and operated. These blades are not supported directly upon the side pieces 3, but upon the four short swinging arms 5, one on either end of each blade member.

30 The swinging arms 5 (see Figs. 2 and 6) are pivotally and loosely mounted upon studs 4 projecting laterally from the members 3 and carry in their lower portions the pivot studs 6 upon two of which, at the opposite ends thereof, the blade members 10 are adapted to be oscillated, by means and in a manner presently to be described.

35 The blades proper having a cutting edge 12 at the respective bottoms thereof when held as shown in Figs. 1 and 2 and have end extensions 13 bent at right angles thereto, the extensions having holes 14 therein through which the studs 6 of the arms 5 pass, and upon which the blade members 10 are pivotally supported. Secured to the side of each extension 13, as by rivets 15, is an upstanding arm 15 carrying at its upper end a pivot stud 16 to which is loosely 40 attached one end of a link 17 which in turn connects with the mechanism next to be described for actuating the blades 10 upon their respective swinging pivotal bearings.

45 The blade actuating device comprises two similar sliding bars 24 suitably mounted

upon the parallel side members 3 of the frame 1 which conveniently serve as guides therefor. The bars 24 have a second handle or gripping piece 21 riveted or otherwise secured to the inner faces of two similar hollow sliding members 22 rectangular in form and loosely fitted upon the guides 3 at the respective sides, to the outer surfaces of which members 22 are secured the side bars 24, above referred to, which extend downwardly to connect with the blade-jaw actuating mechanism. The side bars 24 are also supported at each end upon another sliding member 23 similarly formed and mounted to slide upon the guide 3 in the same manner as the members 22 which support the other end of the pieces 24.

50 Thus it will be seen that by lowering and raising the bars 24, to which the links 17 are attached, such reciprocal action will rock the respective blade members 10 upon their pivotal bearings 6, that is to say, by pressing the handle 21 until the bars 24 are carried to their lowermost position, the edges 12 of the blades 10 will be brought together as shown in Fig. 5, and by exerting an upward pressure upon the handle 21 the bars 24 will be returned to their normal position as shown in Figs. 1 and 2.

55 The pivots 6 on the swinging arms 5 upon which the blade members 10 turn in the manner described, are held in relatively fixed position by means of two cam slots 26 through which the ends of the studs 6 pass, which slots are vertical and parallel at their uppermost parts, swerving obliquely and oppositely as they extend downwardly in each of the two similar cutting plates 30, presently to be described, which plates in turn are suitably supported at 60 the respective sides of and immediately within the side pieces of the blade members 10. The cutting plates 30 having the straight portions 20 are slidably held within the rectangular members 22 and 23, which it has been seen support the gripping member 21 of the slide bars 24 and are themselves 65 slidably mounted upon the side pieces 3 of the frame.

70 The plates 30, being thus held against lateral movement, serve to hold the studs 6 in the ends of the levers 5 firmly in the normal position shown in Fig. 2, the studs resting in the vertical portions of the slots 26 as indicated by broken lines in said figure; and it will readily be seen that upon imparting an upward longitudinal movement to the plates 30, the studs 6 will by action of the outwardly inclined portions of the slots 26 be forced apart, with the result that 75 the blades 10, being suspended also upon the studs 6 as described, will be swung laterally into the position shown in Fig. 6, thereby widening the space between them.

75 To obtain the spreading of the blades in 130

the manner described, the cutting plates 30 having the narrowed slide portions 20 slidably mounted within the sliding bands 22 and 23 on the respective side bars 3 of the frame, are operated by means of link connection with a hand lever 35 loosely suspended upon pivots 36 projecting inwardly from the side bars of the handle 2 of the frame 1.

10 The sliding plates 30 are likewise operated as pointed out by the movement of the hand lever outward and upwardly, which action is accomplished by the means next to be described.

15 Upon each lever at the side of the hand piece 35 projects laterally a stud 36' upon which is loosely attached one end of a short link 38, the other end of which is similarly connected by a stud 39, whereby is provided 20 means for transferring the circular movement of the lever 35 to the longitudinally reciprocal action of the cutting plates in which are provided the slots 26. It will thus be seen that the outward inclination of 25 the slots 26 is adapted to spread the blades 10 while the sliding plate 30 is moving upwardly and withdrawing its cutting end from the material, and conversely when the plate is farthest down, *i. e.*, in the most 30 advantageous position for entering the material, it is firmly holding the blades 10 in their normal cutting position.

For the two-fold purpose of limiting the depth to which the measuring device shall 35 be forced into the medium, and for precipitating the load into the receptacle provided therefor, a horizontal pusher plate and stop gage 40 is attached to the cross head 41 by means of the bracket arms extending downwardly from the cross head and secured in any suitable way to the top surface of the plate and to the cross head. The opposite ends of the cross head 40 extend into the guiding grooves 43 in the respective side 40 members 3 of the frame, as shown clearly in sectional appearance in Fig. 3, a corresponding slot 32 having been cut through the plates 30 to permit the ends of the cross head to pass through. The top of the 45 groove 43 is located at the point at which the cross head 41 stands upon measuring out the required quantity of material; and the groove 43 extends downwardly sufficiently to permit the plate to force out the 50 contents held by the blades 10 and plates 30.

For the purpose of operating the gage pusher plate 40, I prefer to employ a spring action for driving it downwardly, compressing the spring by pressure of the hand, and 55 holding it as thus set by means of a latching device that can be released by the mechanism which spreads the blade 10 inasmuch as at that point is the proper time for precipitating the load, which is accomplished by 60 downward motion of the pusher plate. To

attain this end, any convenient form of compression spring suitably mounted to throw the cross head downwardly with the horizontal plate attached thereto would serve the purpose, but in the preferred form 70 shown, I employ a hinge-like device 55 having leaves 56 and 57, held together by the pintle 58 and a coil spring 59 upon the pintle having its ends bearing outwardly against the respective leaves 56 and 57. 75

The hinge members 56 and 57 are themselves operably attached at their respective outer ends, the leaf 56 being pivotally attached to the cross head and the leaf 57 being similarly connected with the cross bar 80 45 attached to the side pieces 3 of the frame at a point immediately above the top of the grooves 43, which serves the double purpose of stiffening the frame and supplying the support and base of operation for the cross head 41 and blade 40 attached thereto. The plates 30 have suitable slots therein through which the ends of the cross bar 45 pass and which permit of ample vertical movement 85 of the plates 30. 90

Upon the leaf member 56 is an outwardly extending lip 60 convenient to be engaged by the finger in closing the hinge 55 to set the pusher blade, in doing which the cross head is carried to the top of its guiding 95 grooves 43 at which point a catch pin 44 projecting from the side of the cross head engages a spring latch 65 which is attached to the cross bar 45 and holds the cross head in readiness to be thrown downwardly by 100 the spring 59 which has been put in tension by the action of closing the leaves in elevating the cross head.

The latch 65 is suspended from the cross bar 45, being supported upon the pivot stud 105 66 thereon, adjacent one of the side members 3 of the frame. The depending portion of the latch comprises the hook portion 67 which has the usual taper surface 68, by means of which it is cammed to one side in 110 latching below the transversely disposed retaining surface upon which the catch pin 44 is adapted to rest. A spring 68a is coiled upon the stud 66, having one end attached therein, the other end against the side of the 115 latch pressing it in the direction of the side frame nearest thereto, thereby holding the hook portion yieldingly into engaging position therewith.

For releasing the latch 65 a projecting 120 cam surface 70 is provided upon the side of the vertically slidable plate 30, adjacent the latch, the inclined surface of which is adapted to press against a correspondingly tapered arm 69 of the latch member 65. The 125 cam block 70 is located at a point upon the plate 30 immediately below the cam 69 on the latch when the plate 30 is in the normal position; and thence when the latter is carried upwardly for the purpose of spreading 130

the blades in the manner above described, the latch will be thrown to one side and the cross head thereby released so that as it drops to eject the contents the blades 10 will spread simultaneously.

The pusher plate 40 coming into immediate contact with the medium manipulated thereby, it is found highly desirable in handling certain materials to provide means for 10 cleansing the contacting surface of the blade. In the preferred form illustrated to accomplish this purpose, I provide the two stripping or scraping blades 50 which are held operably in place immediately against the 15 under surface of the pusher gage 40 by means of their ends having been turned back over the top surface of the gage plate, the two ends thereof meeting about midway of the top where they are bent upwardly at 20 right angles to form ears 51 to which are operably attached the ends of the levers 52 (see Figs. 1, 7 and 8). These two scrapers are normally held at the respective outer sides of the plate 40 by the levers 52, as 25 shown in Fig. 1, which are secured at their upper ends through the similar links 53 to the stationary cross bar 45. Hence, as the cross head is carried upwardly to the limit of its movement, the levers 52 being held at 30 their respective top ends, will by the action described force the scraping blades 50 in opposite directions until they reach the outer ends of the gage plate 40 upon which they are mounted.

35 The scraping blades 50 are provided with springs 71 which may be firmly attached to the cross head 41 by means of screws or other convenient means, having their ends engaging the pivots by means of which the 40 levers 52 are attached to the ears 51 of the blades, so that when free to do so the springs 71 will force the blades 50 together as shown in Fig. 8. The blades 50 are locked in their separate positions by means of the toggle levers 75 and 76 which are thereby straightened into dead center alinement with the three pivotal points upon which these levers operate. The scraper blades will therefore be held in the outer position described 45 as the pusher plate descends until such time as the toggle levers 75 and 76 may be thrown out of alinement; and to accomplish the unlocking of this member I provide a tripping link 72, one end of which is attached to the 50 pivotal pin connecting the ends of the toggle levers, its other end being provided with a pin 74 adapted to slide in the closed slot of the guide member 73.

The slotted guide member 73 is rigidly 60 secured to the cross bar 45, from which it extends downwardly, its lower end being in alinement with the toggle links 75 when extended as shown in Fig. 1, the length of the slot of the guide 73 being less than the movement of the cross head, so that the links of

the toggle will be tripped, *i. e.*, thrown out of locking alinement as the pusher-gage continues its downward course from the relative positions of the parts as shown in Fig. 7, to its lowermost position as shown in Fig. 8, when the scraper blades have been carried together by action of their springs 71.

The successive operation of the device is as follows: The normal relative position of the operative parts is as shown in Figs. 1 and 2, in which the respective cutting edges 12 of the blades 10 and that of the end plates 30 are in position to enter the medium from which the desired portion is to be withdrawn, until the horizontal plate 40 rests upon the top surface thereof. While the blades are thus buried in the material, the handle 2 is held in one hand of the operator, who with his other hand presses down upon the under handle 21 of the bars 24, 75 forcing that member downwardly, thereby oscillating the blade members 10 upon their pivotal studs 6, into the position shown in Fig. 5, and then the blades may be immediately brought back to normal position by 80 raising the handle 21, before lifting the material that has thus been cut loose from the mother mass on all sides and at the bottom, which will be possible with materials of a nature to adhere to the plates 30 and 85 blades 10, so that it may be bodily lifted and placed over the receptacle intended to receive it. Or, if desired, the blades 10 may be kept in the supporting position shown in Fig. 5, for lifting out the contents.

Having been brought into position for discharging its load, the blades 10 and plates 30 being in immediate contact with the material upon its four sides, there would be a tendency to resist being properly forced 100 out by the plate 40. It has been found desirable in order to reduce the frictional contact of the parts first to spread the blades 10, which is done by turning the hand lever 35 upon its pivotal stud 36, raising it into 105 the position shown in Fig. 6 and thereby through the links 38 sliding the cutting plates 30 upwardly. The elevation of the two plates 30 causes the oblique slots 26 in the plates 30 to cam the blades outwardly 110 upon their pivotal connections 16 with the links 17 into the position shown by broken lines in Fig. 6.

As the blades 10 are caused to spread by the upward movement of the camming plates 30, the cam piece 70 upon the adjacent plate 30 by engaging the cam surface 69 on the latch 65, swings that member upon its pivot 115 into the position shown in Fig. 8, and thereby releases the pusher-gage plate mechanism 120 40 to be carried precipitately downwardly by action of the spring hinge device 55 into the position also shown in said figure.

The parts of my improved mechanism having thus performed their respective func- 130

tions, they are returned to normal positions ready for successive action by the lever handle 35 first having been forced downwardly by action of the flat spring 37 from the horizontal to the vertical positions shown in Figs. 1 and 6, and dotted lines in Fig. 2, which forces the cutting blades 30 into their lowermost position and through the action of the cam slots 26 returns the blade members into the locked position shown in Figs. 1 and 2, and at the same time withdraws the cam piece 70 from contact with the latch 65, which will thereby return to normal position to engage the catch pin 44 of the cross head 41. The pusher-gage mechanism is now forced from the position shown in Fig. 8 to that shown in Figs. 1 and 2, by pressing upwardly with the finger of one hand under the lip 60 of the lower member of the spring hinge device 55, the other hand gripping the handle 2, until the catch 44 snaps into the latch 65.

The device is now in order for again being plunged head on into the medium to be measured, the depth of such descent being limited by the gage plate 40 in the manner described.

In thus having described in more or less particularity the details of the embodiment of my improvement illustrated in the drawings, it is not intended that the scope of my invention should be limited thereby. Thus in its completeness a device is specified which will be found successfully adaptable to many varieties of materials differing in hardness and other properties affecting the efficient manipulation of the device. For example, in connection with the ordinary ice cream which varies in hardness and also has the objectionable quality of adhering to the surfaces with which it comes into contact. In such case it has been found advantageous to spread the cutting blades 10 as shown in Fig. 6, and the preferred form of mechanism is described for accomplishing this specific thing. Yet it is obvious that in employing the device with many other materials, the plunger pusher 40 could successfully emit the load without the assistance furnished in spreading the blades, and furthermore it is also understood that the exact means shown for spreading the blades is not the only one that could be employed for the purpose. Likewise with materials of sufficient cohesiveness to prevent particles adhering to the surface of the pusher plate, the scraping blades 50 might be entirely dispensed with and the device work satisfactorily in connection with such a medium, yet inasmuch as neither the device for spreading the blades 10 nor that for cleansing the under surface of the plate 40 in any way interferes with the successful operation of the device, they have been shown in the complete manner described illustrative of

the universality of uses to which it may be applied, rather than limiting its scope to the specific mechanisms described.

Having described my invention, what I claim is:

1. In a measuring device adapted to separate a portion of merchandise from the bulk thereof, means for cutting through all the contiguous sides and the bottom of the portion to be removed, said cutting means comprising end plates for separating said portion at the ends and oscillating blades for separating at the sides and bottom; and means for discharging said portion intact therefrom. 70

2. In a measuring and filling device adapted to plastic-like material, means for severing and separating a predetermined quantity from the bulk thereof, comprising pivoted jaws and means for opening and closing said jaws; means for discharging the separated quantity comprising a pushing gage; and means comprising a reciprocal slide for relatively widening said jaws when opened. 80

3. In a device of the class described, a frame with a handle; reciprocating end cutting plates; cutting blades or jaws oppositely disposed and pivotally supported upon said frame; means for holding said jaws parallel while forcing the same into plastic-like material; and means for closing and opening said jaws. 90

4. In a device of the class described, a frame with a handle; cutting blades or jaws oppositely disposed and pivotally supported upon said frame; means for holding said jaws parallel while forcing the same into plastic-like material; means for closing and opening said jaws; and means for spreading said jaws when open. 100

5. In a device of the class described, a frame with a handle; cutting blades or jaws oppositely disposed and pivotally supported upon said frame; means for holding said jaws parallel and forcing the same into plastic-like material; means for closing and opening said jaws; and means for spreading said jaws when open, comprising similar sliding members mounted on said frame. 110

6. In a device of the class described, a frame with a handle; cutting blades or jaws oppositely disposed and pivotally supported upon said frame; means for holding said jaws parallel and forcing the same into plastic-like material, means for closing and opening said jaws; means for spreading said jaws when open, comprising similar sliding members mounted on said frame; and means comprising springs for holding said spreading means in normally closed position. 120

7. In a measuring device adapted to separate a portion of merchandise from bulk thereof, means for cutting through all the contiguous sides and bottom of the portion 130

- 6 to be removed, said cutting means comprising cutting blades for the sides, a portion of said blades adapted to be oscillated from relatively vertical to horizontal positions, 5 thereby to cut through the bottom of said portion.
8. In a measuring device adapted to separate a portion of merchandise from bulk thereof, means for thrusting said device 10 longitudinally into the bulk to be divided, comprising holding means and cutting blades oppositely disposed to said holding means; means for gaging the depth to which said blades are adapted to enter said bulk; 15 means for severing and thereafter lifting the material cut from said bulk; and spring operated means whereby said gage is caused to discharge the separated portion from said device.
- 20 9. In a measuring device adapted to separate a predetermined portion of merchandise from bulk thereof, cutting blades thereon; means for thrusting said device longitudinally into the bulk to be divided in the 25 direction of said blades; means for predetermineding the depth said blades enter said bulk, comprising a transverse gage plate; means for causing said gage plate to move longitudinally of said device; and means 30 comprising scraping blades for removing matter from the surface of said plate.
10. In a measuring device for separating a portion of material from bulk thereof, means for inserting said device to a predetermined depth in said bulk, comprising 35 a handle at one end of said device; cutting blades at the opposite end thereof for cutting the sides of the portion to be removed and shiftable to cut transversely of the 40 device to sever the portion from the bulk, a transverse gage plate intermediate said handle and blades; and means for removing extraneous matter from said plate.
11. In a measuring device for separating 45 a portion of material from bulk thereof, means for inserting said device to a predetermined depth in said bulk, comprising a handle at one end of said device; shiftable cutting blades at the opposite end thereof 50 and a transverse gage plate intermediate said handle and blades; means for removing extraneous matter from said plate, comprising blades on said plate adjacent the surface thereof and means for reciprocating 55 said blades across the face thereof.
12. In a measuring device adapted to separate a predetermined portion of merchandise from the bulk thereof, a handle and cutting blades oppositely disposed therefrom; means for sinking said blades into the bulk to be divided to a predetermined extent, comprising a transverse gage plate; means for sliding said plate longitudinally of said device; cleansing blades adapted to 60 scrape the surface of said plate; spring actuated means for moving said cleansing blades synchronously with the sliding of said plate; means comprising toggle links for locking said cleansing blades against the action of said spring actuating means; and means comprising a slotted guide member and connecting link for tripping said toggle at a predetermined point of the travel of said plate. 65
13. In a device adapted to separate a prescribed portion of merchandise from the bulk thereof, a frame comprising a handle and cutting blades at the respective ends and a transversely disposed pusher gage slidably mounted on said frame intermediate said handle and cutting blades; spring actuated scraper blades slidably supported on said gage; and means for sliding said blades synchronously with the sliding of said gage, both of said sliding devices simultaneously 70 ending their sliding movements. 75
14. In a device adapted to separate a prescribed portion of merchandise from the bulk thereof, a frame comprising a handle, cutting blades oppositely disposed thereto, 80 and a sliding gage transversely mounted in said frame; spring actuating means comprising a spring device for impelling said gage in the direction of the cutting blades; a latch device for holding said gage against 85 the action of said spring device; oppositely disposed scraping blades slidably mounted on said gage; spring actuating means for 90 forcing said scraping blades together; toggle links for holding said scraping blades in a 95 locked separated position; means for releasing said latch, comprising a slide having a cam block thereon; and means connected with the slide for releasing said toggle locking links. 100
- 105 In testimony whereof, I have signed my name to this specification this 14th day of December, 1917.

HERMANN J. SCHUBERT
